UNITED STATES PATENT OFFICE

CHARLES S. CRAWFORD, OF DETROIT, MICHIGAN, ASSIGNOR TO GENERAL MOTORS CORPORATION, OF DETROIT, MICHIGAN, A CORPORATION OF DELAWARE

IGNITION-WIRE CONDUIT

Application filed December 31, 1928. Serial No. 329,447.

Although the present invention is referred to simply as an ignition wire conduit, it should be understood that said invention is directed more particularly to the provision 5 of means for supporting a cover element serving incidentally in spacing and/or protecting the high-tension wires used in connecting the so-called "distributor head" of an internal combustion engine with a series of 10 spark plugs; and preferred embodiments of this invention may accordingly include special plates, adapted to be removably secured to engine blocks and to provide suitable longitudinal passages or channels to receive sets of 15 such wires,—said passages or channels being preferably provided not only with entrance openings, suitable to receive a plurality of the mentioned wires, but with separate openings through which said wires may be respectively led, for attachment to the mentioned 20 spark plugs.

In all forms of the present invention, the mentioned plate may be formed from a sheet material and adapted to be removably retained by means such as a peripheral or other set of screws; said plate may be provided with a series of apertures corresponding in number and position with the mentioned spark plugs; and either the mentioned plate 25 or a subsidiary plate, when used, or both, may be provided with a longitudinal concavity and/or with the mentioned separate apertures for the respective wires by which high tension current is delivered to said spark 30 plugs.

Other objects of this invention, including various optional and alternative features hereinafter referred to, may be best appreciated from the following descriptions taken 35 in connection with the appended claims and the accompanying drawings.

Fig. 1 is a side elevational view, showing one advantageous embodiment of the present invention as applied to a six-cylinder engine 40 whose spark plugs are horizontally arranged in a suitable lateral compartment,—parts being broken away.

Fig. 2 is, for the most part, a partial vertical section taken in a broken plane such as 45 that indicated by the line 2—2 of Figure 1.

Fig. 3 is an enlarged detail view, corresponding to a central portion of Figure 2, but showing alternative and optional features and omitting all wires.

Fig. 4 is a horizontal sectional view showing an alternative form, although taken in a plane such as that suggested by line 4—4 of Figure 1, or by the line 4—4 of Fig. 5.

Fig. 5 is a sectional view, taken substantially as indicated by the line 5—5 of Figure 4, and showing features which permit alternative arrangements of parts.

Fig. 6 is a view, comparable with Figure 5, showing a simplified, primitive, or partial embodiment of the invention.

Fig. 7 is a partial elevational view showing another simple or partial embodiment of the invention, parts being broken away.

Referring first to features shown in Figures 1, 2, and 3, an engine block 10 is shown as laterally provided with a compartment 11, adapted to contain various movable and/or fixed parts,—including a series of six spark plugs 12; said engine block is shown as also supporting a distributor head 13, suitably positioned for use in connection with high tension wires 14, 14^a, 14^b, 14^c, 14^d, and 14^e to assure properly timed sparking of the respective spark plugs 12; and the present invention should be understood to relate particularly to the provision of a cover which serves also as supporting, housing, spacing and/or positioning means for said wires or equivalent conductors.

For the purposes last referred to, a removable main cover plate 15, shown as secured by screws 16 and as provided with a series of plug-passing openings 17, opposite the respective spark plugs 12 (to permit independent withdrawal, inspection and/or replacement of the respective spark plugs without necessitating removal of said plate) is shown as provided also with a longitudinally-extending passage, channel or depression 18, adapted to receive and partially or completely to enclose said wires.

As best shown in Figures 2 and 3, the depression 18 may extend inwardly; and it may be closed, to any desired degree, by means such as a removable or other subsidiary and

flat or oppositely concaved cover plate 19. The latter plate, when provided, may be removably retained by any suitable means, such as catches 20 and/or screws 21—the latter being shown in Figure 2 as engaged by nuts 22 and shown in Figure 3 as threaded into bosses 23, integral with the channel portion 18 of cover plate 15; and the subsidiary plate 19 is shown as provided not only with a substantially central and flared upper or main opening 24, affording a common entrance for the respective wires 14—14^e, but with a series of longitudinally spaced outlet openings 25, 25^a, 25^b, 25^c, 25^d, 25^e for said wires. It will be obvious that, assuming the cover plate 19 to be separately formed and removable in the indicated manner, the mentioned openings therein may either be provided with uninterrupted edges or any or all of said openings may be provided somewhat as suggested at 24', 25' and 25'^e (Fig. 1) with slots so positioned as to permit the positioning of said subsidiary cover plates after both ends of the mentioned wires are secured and without disconnection thereof; and in case an additional wire, such as a main feed wire 14^f, is required to be brought to or from the distributor head 13, provision may be made therefor either externally of or within the channel 18,—as by the provision of an additional opening 25^f, near one end of the subsidiary plate 19.

In the alternative form shown in Figures 4 and 5, a channel 18' is provided by outwardly embossing a plate 15' covering a spark plug compartment 11' in engine block 10'; and an oppositely concaved subsidiary cover plate 19' is shown as permanently and inwardly secured thereto, as by welding at the edges thereof. In this embodiment, a substantially central and common inlet opening 24' is shown as positioned at a lower level than alternative series of outlet openings 25^a and 25^b. In order to adapt the plate 15' to use under exceptional conditions, in which spark plugs 12 may be housed entirely within the compartment 11', plug-passing openings 17' may be provided with separate closures 26, for a dust-excluding or other effect, the interior set of openings 25^b being provided for optional use in the general manner suggested in Figure 5.

Fig. 6 shows a cover plate 15'' which is provided with plug-passing openings 17'' and with a channel 18'' having wire-passing openings 24'' and 25'',—the channel 18'' and the use of any subsidiary cover plate therewith being optional.

Fig. 7 shows a substantially flat plate 15''' from which tongues are struck in such manner as to provide holes 28 and clips suitable for use in retaining wires.

It should be understood that, in the various embodiments of the present invention, cover plates adapted to serve in the described manner may be disposed either in a substantially

vertical plane or in any other desired plane or planes; and that, for the identification of the respective high tension wires, the insulation thereon may be given distinctive colors in case parts thereof are concealed. In any case, cover plates specialized in the general manner described will be seen to support and assure the spacing and orderly arrangement of the respective conductors in out-of-the-way positions, maintaining the separateness thereof in such manner that any wire may be identified, inspected and/or replaced without disturbing the remaining wires; and even the simpler embodiments of the present invention will be seen to serve for incidental dust-excluding and similar effects and to obviate danger of accidental damage to the high tension conductors during any necessary repairs or adjustments of associated parts.

Although the foregoing description has included a plurality of alternative embodiments, and also suggestions as to optional details and modes of use, it should be understood that not only various features of this invention might be independently employed but that numerous additional modifications might easily be devised,—all without involving the slightest departure from the scope of the invention.

I claim:

1. For use upon an internal combustion engine provided with a compartment wherein are disposed a plurality of spark plugs, each spark plug being connected with a separate conductor: a cover plate adapted to form a side wall of said compartment,—said plate being formed of sheet material having a longitudinally-extending channel formed therein and apertured to admit said conductors.

2. For use upon an internal combustion engine provided with a compartment wherein are disposed a plurality of spark plugs, each spark plug being connected with a separate conductor: a cover plate carrying a subsidiary plate and adapted to form a side wall of said compartment and to provide a common passage for said conductors,—walls of said passage being formed by oppositely disposed concavities in said plates.

3. For use upon an internal combustion engine provided with a compartment wherein are disposed a plurality of spark plugs, each spark plug being connected with a separate conductor: a sheet metal cover plate adapted to form a side wall of said compartment, and to provide one wall of a common passage for said conductors,—said passage being completed by an oppositely disposed element and provided with separate outlet openings for said conductors.

4. For use upon an internal combustion engine provided with a compartment wherein are disposed a plurality of spark plugs, each spark plug being connected with a separate conductor: a cover plate adapted to form a

side wall of said compartment and to provide a common passage for said conductors, said passage being provided with a substantially central main opening and with separate outlet openings for said conductors.

5. For use upon an engine block provided with a plurality of spark plugs having separate conductors connected therewith: means comprising a main plate carried by said block, 10 for so supporting said conductors as to protect and space the same in a manner permitting separate replacement thereof,—said means comprising also a subsidiary plate secured to said main plate and at least one of 15 said plates being apertured suitably to permit passage of both said conductors and said spark plugs therethrough.

6. For use upon an engine block provided with a plurality of spark plugs having separate conductors connected therewith: retaining means carried by said block for so supporting said conductors as to space the same in a manner permitting separate replacement thereof,—said means comprising an apertured cover plate secured to said block and provided with a longitudinal depression adapted to receive said conductors.

7. For use upon an engine block provided with a plurality of spark plugs having separate conductors connected therewith: retaining means carried by said block for so supporting said conductors as to protect and space the same in a manner permitting separate replacement thereof,—said means comprising a cover plate secured to said block and provided with a subsidiary plate, said plates being so formed as to provide therebetween longitudinal passage for said conductors.

40 In testimony whereof I affix my signature.
CHARLES S. CRAWFORD.
